UNITED STATES PATENT OFFICE.

ROBERT M. REID, OF COLORADO SPRINGS, COLORADO.

MOUNTING FOR GLASSES.

1,333,575.

Specification of Letters Patent.

Patented Mar. 9, 1920.

Application filed June 13, 1917. Serial No. 174,608.

To all whom it may concern:

Be it known that I, ROBERT M. REID, a citizen of the United States, residing at Colorado Springs, in the county of El Paso 5 and State of Colorado, have invented a certain new and useful Improvement in Mountings for Glasses, of which the following is a specification.

This invention relates to glasses ordinarily worn by people, and particularly to what are technically known as eye-glasses in which the glass lenses are wholly supported from and attached to the nose of the wearer.

15 The object of the invention is to provide a novel form of nose-piece and mechanism for attaching the glass lenses thereto in such a way that an unusually strong construction is obtained instead of puncturing the lenses 20 as has always been necessary heretofore, while the outer rim of each glass lens is supported by a substantially invisible metallic band.

The invention consists in means for carrying out the foregoing objects; which can be easily and cheaply made; which is satisfactory in use, and is not readily liable to get out of order. The invention consists more particularly in the features and details 30 of construction hereafter more fully set forth in the specification and claims.

Referring to the drawings in which similar numerals indicate the same parts throughout the several views,

35 Figure 1 is a front view of a pair of eye-glasses constructed in accordance with this invention in its preferred form.

Fig. 2 is a plan view of the device shown in Fig. 1.

40 Fig. 3 is a sectional end view of the lens enlarged, and taken on the line 3—3 of Fig. 1.

Fig. 4 is a correspondingly enlarged plan view taken on the line 4 of Fig. 1.

45 Fig. 5 is a perspective view of the nose-piece frame and the band which binds a lens, all other parts being removed.

In constructing the device of this invention in its preferred form, a nose-piece 10 is 50 provided. Each end of this nose-piece is divided or split in the process of manufacture into two parallel horizontal arms 12 and 14, separated like the arms of a U whose base is the nose-piece 10. The end of arm 55 12 terminates in an upwardly rising finger

16 embracing a portion of the circumference of the adjacent lens 18, and two side fingers 20 engaging opposite sides of the lens in the ordinary manner. Similarly arm 14 is provided with a downwardly extending finger 60 22 corresponding to finger 16, and two side fingers 24 corresponding to fingers 20. The forked fingers 20 and 24 serve the very useful purpose of supporting the lens against sidewise movement with reference to the 65 nose piece. The arms 12 and 14 are connected together by a screw 26 bearing right hand threads on one end and left hand threads on the other where it engages respectively the two arms in question, with 70 the result that rotating the screw 26 in one direction tends to draw the arms 12 and 14 together while rotating it in the other direction tends to separate them.

Journaled upon each screw 26 is a nose 75 gripping device 28 controlled by a spring 30 of the ordinary type, and forming no part of this invention. This nose grip may be omitted when the glasses are to be used in spectacle form with bows attached at the 80 outer edges of the lenses.

Instead of puncturing the lenses 18 adjacent to the nose-piece and securing them thereto by rivets in the ordinary manner, the lenses are provided on their outer circumferences with V-shaped recesses 32, clearly appearing in Fig. 3, in which are placed circumferential bands of fine wire 34, the opposite ends of these wire bands being provided with transverse cross-bars 90 or hooks 36, adapted, as clearly shown in Fig. 5, to hook into notches 38 provided at the juncture of the respective arms 12 and 14 and their respective fingers 16 and 22.

Attention is especially called to the fact 95 that in the construction above set forth, the cross bars or hooks 36 on the ends of the wire band engage the nose piece mechanism at single points, thus doing away with the necessity of making more than a single perforation therein for each end of the band, this being especially important where there is so little stock material. The construction has a further advantage that in assembling the eye-glasses, if the parts fit too tight, adjustment may readily be made by slightly filing the cross bars or hooks 36 until all the mechanism co-operates properly.

In assembling the mechanism of this invention, the operator takes a nose-piece con- 110

structed as shown and first loosens up the screw 26. He then takes the lens 18 which is to be applied, places around it the previously prepared band 34 and attaches the 5 hooks 36 over the notches 38 in the manner described. He then tightens up the screw 26 thereby forcing the arms 12 and 14 together and placing tension upon the band 34 sufficient to cause it to firmly grip the 10 lens 18 and hold it in place. The operation of removing the lens is obviously merely a reversal of the movements just described.

The fact that the nose piece is made with an integral U-shaped opening, whose arms 15 12 and 14, are sprung together by a single contracting mechanism, in the particular case here illustrated, the screw 26, is very important in that it eliminates parts which might become detached when the screw 20 loosens or is removed. In the construction shown, the screw 26 can loosen materially without any of the parts being able to move sufficiently to release the lens.

In actual practice, the band 34 may be 25 made so fine as to be practically invisible so that glasses constructed in accordance with this invention have all the advantages of the ordinary rimless eye-glasses together with the very great advantage that the lenses instead of being weakened by having one or 30 more holes cut in them for attachment to the nose-piece are, on the other hand, strengthened by the adding of the supporting band 34.

35 Where ordinary bow glasses are desired, the bows may be attached in any suitable manner to the outer edges of the lenses 18, one possible construction being to solder the bow supports to the band 34 at the 40 points named.

The groove 32 is very important as it seems to render the band 34 substantially invisible.

The band 34 may, of course, be of metal 45 or any other suitable material.

Having thus described my invention, what I claim as new and desire to secure by Letters Patent, is:

1. In mechanism of the class described, 50 a nose-piece, a lens, a band around the lens, an expandible and contractible mechanism non-separable as to its members on the end of the nose-piece engaged by the ends of said band in single openings, adapted to detachably secure the band around the lens.

2. In mechanism of the class described, a nose-piece, a lens, a band around the lens, and expandible and contractible mechanism integral with the end of the nose-piece 60 detachably engaged by the ends of said band in single openings one for each end of the band adapted to detachably secure the band about the lens.

3. In mechanism of the class described, a 65 nose-piece, a U-shaped fork integral on the

end of the nose-piece, means for supporting a lens on the end of said U-shaped arms, fingers on said supporting arms embracing opposite sides of the lens, a band around the lens detachably connectible to said arms, 70 and means detachably forcing the arms together to cause the band to grip the lens, for the purpose set forth.

4. In a device of the class described, a nose-piece forked at its ends so as to form a 75 U-shaped recess opening outward toward the lens, a lens abutting the end of the nose-piece, a band around the lens having one end attached to a forked end of the nose-piece, a hook on the other end of the band 80 detachably engaging the other forked end of the nose-piece, and means for detachably contracting the fork portions on the nose-piece to tighten the band, for the purposes set forth.

5. In mechanism of the class described, a nose piece, expandible and contractible mechanism at the end of the nose piece, a shouldered opening, one for each arm of the expandible and contractible mechanism, a 90 lens, a band around the lens, a T-shaped hook on each end of the band, said band having one end secured to one part of the expandible and contractible mechanism, and the hook on the other end of the band 95 engaging another portion of the expandible and contractible mechanism in a single opening, for the purposes set forth.

6. In a mechanism of the class described, a nose-piece, an expandible and contractible 100 mechanism at the end of the nose-piece, a shouldered opening in each arm of the expandible and contractible mechanism, a lens, a band around the lens having one end secured to one part of the expandible and contractible mechanism, and a coupling device 105 connecting the second end of the band with another portion of the expandible and contractible mechanism at a single opening, said coupling device increasing in cross section 110 toward the end of the band whereby adjustments may be made by filing off a portion of the coupling device for the purposes set forth.

7. In mechanism of the class described, a 115 nose-piece, an unperforated lens, an expandible and contractible mechanism at the end of the nose-piece, a band around the lens provided at one end with a T-shaped hook to detachably connect the band to the expandible and contractible mechanism, and a coupling device connecting the second end of the band with another part of the expandible and contractible mechanism at a single opening, said coupling device enlarged 120 toward the end of the band to provide for adjustments by filing off a portion of the coupling device, fingers on the expandible and contractible mechanism extending toward the center of the lens and forming a 125 130

slot whereby the hook is guided into position during the operation of assembling, for the purposes set forth.

8. In mechanism of the class described, a nose piece, an unperforated lens, oppositely extending members on the end of the nose piece following the circumference of the lens, fingers on the end of the nose piece extending toward the center of the lens and embracing it, and a band around the lens

detachably securing the lens to the end of the nose piece.

In witness whereof I have hereunto subscribed my name in the presence of two witnesses.

ROBERT M. REID.
